T. LUND.

APPARATUS FOR HANDLING STAIN.

APPLICATION FILED FEB. 18, 1918.

1,391,395.

Patented Sept. 20, 1921.

INVENTOR
Thomas Lund
By his Attorney
Kelson McDonald

UNITED STATES PATENT OFFICE.

THOMAS LUND, OF BEVERLY, MASSACHUSETTS, ASSIGNOR TO UNITED SHOE MACHINERY CORPORATION, OF PATERSON, NEW JERSEY, A CORPORATION OF NEW JERSEY.

APPARATUS FOR HANDLING STAIN.

1,391,395.

Specification of Letters Patent. Patented Sept. 20, 1921.

Application filed February 18, 1918. Serial No. 217,882.

To all whom it may concern:

Be it known that I, THOMAS LUND, a citizen of the United States, residing at Beverly, in the county of Essex and State of Massachusetts, have invented certain Improvements in Apparatus for Handling Stain, of which the following description, in connection with the accompanying drawings, is a specification, like reference characters 10 on the drawings indicating like parts in the several figures.

This invention relates to an apparatus for storing and stirring liquid coloring matter and is herein illustrated as embodied in an 15 apparatus for storing and stirring stain or blacking used in the manufacture of boots and shoes.

Stain, used in the manufacture of boots and shoes, is made in accordance with various formulæ but is all substantially alike in that it comprises a suspension of solids such as wax, coloring matter, filling matter, etc. in a liquid which is usually largely water. It is therefore, necessary to stir the 25 stain prior to using it and usually while it is being used.

The present invention relates to an apparatus for thoroughly performing the stirring operation, for storing the stain and for 30 protecting it from dust and other foreign matter.

According to one feature of the invention, there is provided a cylindrical casing having circular shelves for supporting the unstirred 35 stain, a top for the casing to support the liquid while being stirred, a rotatably stirrer supported vertically over the casing for stirring the liquid, and a rim around the top of the casing to retain any liquid that 40 may be spilled.

Other features comprise improved means for driving the stirrer and for connecting it with and disconnecting it from the driving means.

45 These and other features of the invention, including certain details of construction and combinations of parts, will be described as embodied in an illustrative apparatus and pointed out in the appended claims.

50 Referring to the accompanying drawing,—

The figure is a perspective of an apparatus in which the present invention is embodied, the stirrer being shown in dotted lines in its 55 raised position.

The casing 1 is supported on a pedestal 3 having a base 5. Formed in the casing is a compartment having circular shelves 7 adapted to hold bowls of different colored stain, the compartment being adapted to be 60 closed by a door 9 having a spring catch 11. The top of the stand is a table 13 adapted to support a bowl 15 of stain, a rim 17 being provided to hold any stain which may accidentally fall upon the table. 65

Rising from the table or support is a standard 19 provided with a seat 119 for a small electric motor 21, the horizontal shaft of which carries at its end a worm 23. An arm on the standard 19 overhangs the table 70 13, and in this portion is formed a vertical bore to receive the stem 25 of the stirrer. A worm gear 27 which meshes with the worm 23 and is rotatably mounted in the standard 19 has a bore which is alined with the vertical bore referred to above; and the stem 25 passes loosely through these alined bores and has a knob 125 at its upper end which may be grasped when it is desired to raise the stirrer. In order to cause the stirrer to 75 be rotated by the gear when the parts are in the full line positions, there are formed upon the worm gear 27 a pair of widely spaced projections, one of which is indicated at 29, and upon the stem 25 two fingers 80 extending outwardly and downwardly with the rounded ends. Upon moving the stem from the dotted line position to the full line position, the rounded ends will normally enter between the widely spaced projections 85 90 without any rotary positioning movement being necessary, but, should the fingers come nearly over the projections, the rounded ends will engage the projections and cause such slight rotation of the stem as is necessary to 95 bring the parts to a driving position. The stirring tool 33 is fast to the lower end of the stem 25. In order to prevent dirt and oil on the worm and gear from dropping into the bowl of stain, said worm and gear 100 are received in an irregularly cup-shaped casing 37 which is herein shown as integral with the standard 19.

In the use of the apparatus, one or more bowls of stain, for example two bowls, one 105 containing brown and the other black stain, are stored on the shelves 7 with the door 9 of the compartment closed. When it is desired to use one of the stains, the bowl containing it is taken from the compartment, the 110

stem 25 raised by means of the knob 125, the bowl placed upon the support, and the stem lowered. The bowl and the parts of the apparatus are at that time in the positions 5 shown in full lines in the figure. The operator may then dip a brush into the stain and apply it to the boot or shoe, the stirrer continuing to agitate the stain as long as the stain is being used. There is thus provided 10 a portable apparatus for storing and stirring stain which may be moved from one location to another as may be desired.

Having thus described my invention, what I claim as new and desire to secure by Letters Patent is:

1. An apparatus for stirring stain comprising a table for supporting the liquid to be stirred, a motor carrying standard secured to the table and having an arm overhanging the liquid, a cup-shaped oil retaining casing carried by the overhanging arm, a worm gear and a driving worm rotatable 20

within the casing, there being vertically alined bores through the overhanging arm and the worm gear, a stirrer having a stem 25 slidable through the bores, a pair of fingers on the stem extending outwardly and downwardly and with rounded ends, and a pair of widely spaced projections formed on the gear whereby the stem can be readily placed 30 in driving engagement with the gear upon downward movement of the stem.

2. In an apparatus for storing and stirring stain of different colors, a stand comprising a cylindrical casing having circular shelves for supporting bowls of unstirred stain, a top for the casing to support the liquid while being stirred, a rotatable stirrer supported vertically over the casing for stirring the liquid, and a rim around the top 40 of the casing to retain the liquid spilled.

In testimony whereof I have signed my name to this specification.

THOMAS LUND.
